Primary Examiner — Bridget L. Eland*Assistant Examiner* — Lauren McVey(57) **CLAIM**

The ornamental design for a sunglass book cover, as shown and described.

DESCRIPTION

FIG. 1 is a front view of a sunglass book cover showing my new design;

FIG. 2 is a rear view thereof;

FIG. 3 is a left-side view thereof;

FIG. 4 is a right-side view thereof;

FIG. 5 is a top plan view thereof;

FIG. 6 is a bottom plan view thereof; and,

FIG. 7 is a perspective view of the sunglass book cover. The broken lines are directed to environment and form no part of the claimed design.
